SHOE HOLDING DEVICE

Christian N. Lyngby, Chicago, Ill.

Application November 14, 1945, Serial No. 628,455

1 Claim. (Cl. 12—123)

1

This invention relates to a device for holding footgear, i. e., a boot or a shoe.

One object of the invention is to provide a device which can hold a shoe or boot in a secure position suitable for cleaning and polishing thereof.

Another object of the invention is to provide a structure which enables the shoe or boot to be rapidly and easily clamped and released.

Further objects and advantages will become apparent from a consideration of the following description.

In the drawings,

Fig. 1 is a perspective view of the device showing the clamp in use;

Fig. 2 is a partial side-elevational view of the same; and

Fig. 3 is a cross section taken on line 3—3 of Fig. 2.

Referring now to the drawings, there is provided a frame 10 substantially of C-shape and comprising resilient material, e. g., a steel bar suitably formed and of such cross section as to possess the desired resiliency. Interposed between the top and bottom arms 11 and 12, respectively, of the frame 10 is the clamp 13 of wood or any suitable material and consisting of the top and bottom sections 14 and 15 articulated end to end to comprise a toggle joint, the hinge 16 providing relative movement therebetween. A swivel member, for example a wood screw 17, passed loosely through an aperture 18 in the leg 11 and entering the upper end of the section 14, is provided to permit positioning of the clamp 13 in locking and unlocked positions.

The lower end of the portion 15 is slotted as at 21 to form a pair of fingers 22—22, the ends of the fingers being rounded, if desired, in order not to damage the insole of the shoe.

Attached to the lower arm 12, as by wood screws 23 passing through suitable apertures in the arm, is the shoe rest 24 suitably formed of wood, as shown, and having a dished sole portion 25 in order that the curved sole may be retained against lateral shifting to some extent while polishing proceeds. The rest 24 also includes a platform 26 on which the heel may rest, and interposed between the portion 25 and the platform 26 is the cleat 27 which may be integral with or attached to the rest 24.

The device may be secured to the frame of a door or to any other suitable fixed support by passing screws through apertures 30 in the frame 10, or in lieu thereof, and to avoid marring the woodwork, a pair of rubber suction cups may

2

form a permanent part of the device whereby the same may be attached to a smooth surface, as is well known. It is within the contemplation of my invention also to support the device on a suitable stand which may rest on the floor, the base thereof being of such nature that the user may steady the same with one foot while cleaning and polishing the shoe.

The device is capable of being used either with or without a shoe tree being inserted in the shoe. It will be obvious that if a conventional shoe tree is first inserted in the shoe, it is substantially stiffened and lends itself more readily to an efficient polishing action. For this purpose any of many common types of shoe trees may be employed, but in any case the tree will possess a shank 31 joining the toe and heel portions thereof, the aperture 21 being adapted for clearance of the shank, as shown.

Assuming that the shoe tree is to be used, as indicated in the figures, the same is first inserted in the shoe and the shoe deposited on the rest 24, the breast of the heel abutting the rear of the cleat 27, whereupon the clamp 13 is brought from the dotted-line position shown in Fig. 1 to a position wherein the clamp is still loose but with the fingers 22—22 abutting the insole. While holding the bottom of the fingers 22 pressed against the insole of the shoe and in a position just to the rear of the cleat 27, the portions 14 and 15 are articulated about the hinge 16 to set up a toggle action intermediate the arm 11 and the shoe.

It will be noted that the nature of the joint of the clamp 13 is such that when thrust into clamping position there is an over-centering action, as clearly shown from Fig. 1, and whereby the toggle-joint effect is efficiently maintained. It will be understood that there is sufficient clearance between the adjacent ends of the portions 14 and 15 to permit the clamp 13 to be thrust off-center as indicated. Moreover, the resiliency of the frame 10 is such as to impart a substantial thrust through the clamp 13 and against the shoe. Due to the over-center position of the clamp 13, the portion 15 takes an inclined position, as shown in Fig. 2, whereby the shoe is to a substantial extent forced toward a position against the cleat 27. Otherwise stated, there is a dual holding action, downwardly and forwardly.

To release the shoe after polishing, the clamp 13 is reversely articulated by grasping the same near the hinge 16 and drawing the clamp forwardly to the dotted-line position. Manipulation of the clamp 13 to unlocked position and clear

of the shoe uppers is facilitated by the swivel joint including the screw 17 and aperture 18.

From the foregoing it will be apprehended that I have provided a device for the purpose outlined, which includes a minimum number of parts of inexpensive construction. Hence it is foolproof and simple enough to appeal to the householder. It is not intended to limit the invention to the particular form shown and described, which is only one exemplification thereof. For example, the device may be adapted to cobbling or the manufacture of footgear, or to any other uses other than cleaning and polishing thereof.

While I have shown particular embodiments of my invention, it will be understood, of course, that I do not wish to be limited thereto, since many modifications may be made, and I therefore contemplate by the appended claims to cover any such modifications as fall within the true spirit and scope of my invention.

Having thus described my invention, what I claim and desire to secure by Letters Patent is:

A device for holding an article of footgear comprising in combination a frame having a pair of

parallelly disposed, laterally extending arms one above the other, the lower arm including a rest upon which the article may be deposited and the upper arm having means to support a two-part 5 clamping member, said means including a swivel joint associated with the upper part, and means intermediate the said two parts for relative articulation of the same, the bottom extremity of the lower part having an abutment to clamp 10 the article against the rest.

CHRISTIAN N. LYNGBY.
